WITNESS:

UNITED STATES PATENT OFFICE.

GEORGE F. EDMONDS, OF LEAVENWORTH, KANSAS.

MOISTURE-COLLECTOR.

1,346,742.

Specification of Letters Patent.

Patented July 13, 1920.

Application filed March 8, 1920. Serial No. 364,337.

To all whom it may concern:

Be it known that I, GEORGE F. EDMONDS, a citizen of the United States, residing at Leavenworth, in the county of Leavenworth 5 and State of Kansas, have invented new and useful Improvements in Moisture-Collectors, of which the following is a specification.

This invention relates to a device for 10 catching water caused by the melting of ice on the glass of the door, the object of the invention being to prevent water running off on to the floor where it is likely to freeze, making it dangerous to walk upon 15 and also preventing the door from being opened.

In carrying out my invention I provide a tray for collecting the water and directing it to a cup, said tray having a rubber strip 20 thereon for engaging the glass.

This invention also consists in certain other features of construction and in the combination and arrangement of the several parts, to be hereinafter fully described, 25 illustrated in the accompanying drawings and specifically pointed out in the appended claims.

In describing my invention in detail, reference will be had to the accompanying 30 drawings wherein like characters denote like or corresponding parts throughout the several views, and in which:—

Figure 1 is a view showing the invention in use upon a door.

35 Fig. 2 is a plan view of the device.

Fig. 3 is a central longitudinal sectional view through Fig. 1.

In these views 1 indicates the door and 2 the glass panel therein. My improved device 40 consists of a metal tray 3 having its ends bent upwardly as at 4 and provided with holes for receiving the screws to secure the device to the door. The inner edge of the tray is bent upwardly and this edge 45 is received by a triangle-shaped strip 5 of rubber or the like, the strip being slotted, as at 6, to receive this edge. The front of the tray has its edges converging to the center and these edges are turned upwardly, 50 as at 7. The bottom of the tray slopes downwardly from each side toward the center. At the center the outer part of the tray is cut-away to provide an opening 8 and a part of the metal is bent downwardly

to form a tongue 9. This tongue is hooked 55 and is adapted to support a cup 10 which is so supported by the tongue as to catch the water passing through the opening 8.

The device is placed at the bottom of the glass panel with the rubber strip engaging 60 the bottom of said panel so that the water running down said panel will flow over the inclined face of the rubber strip on to the tray and due to the sloping bottom of said tray will pass to the center of the same 65 and pass through the opening 8 into the cup. Before the cup becomes filled it may be removed and emptied and replaced. In this way the water from the melted ice on the glass panel will be prevented from 70 reaching the floor where it is liable to freeze and prevent the door from being opened.

It is thought from the foregoing description that the advantages and novel features of my invention will be readily apparent. 75

I desire it to be understood that I may make changes in the construction and in the combination and arrangement of the several parts, provided that such changes fall within the scope of the appended claims. 80

What I claim is:—

1. A device of the class described comprising a tray having tabs adapted to be secured to the door, the inner edge of said tray being straight and bent upwardly at 85 an angle, a rubber strip of triangular-shape having a slot in its inclined face for receiving said inclined edge, said tray having an opening in its center for the outlet of water and a cup removably connected with the 90 tray and suspended under said opening.

2. A device of the class described comprising a tray formed of metal and having a tab at each end for connecting it with the door, a rubber strip connected with the inner edge of the tray and engaging the glass plate in the door, said tray having its bottom sloping downwardly from its ends toward the center, the outer edges of the tray being curved upwardly, the central part of 100 said curved edge being cut-away to form an opening and the metal from the opening being bent downwardly to form a hooked tongue and a cup suspended from said tray under the opening. 105

In testimony whereof I affix my signature.

GEORGE F. EDMONDS.
